US00D889943S

(12) **United States Design Patent** (10) **Patent No.:** **US D889,943 S**
(45) **Date of Patent:** **** Jul. 14, 2020**

(54) **PIPE SUPPORT**

(71) Applicant: **Southwest Agri-Plastics, Inc.**, Addison, TX (US)

(72) Inventors: **Paul D. Phillips**, Frisco, TX (US); **Victor A. Sahm, III**, Dallas, TX (US); **Matthew A. Hanson**, Celina, TX (US)

(73) Assignee: **Southwest Agri-Plastics, Inc.**, Dallas, TX (US)

(**) Term: **15 Years**

(21) Appl. No.: **29/676,359**

(22) Filed: **Jan. 10, 2019**

(51) **LOC (12) Cl.** **09-06**

(52) **U.S. Cl.**

USPC **D8/356**

(57) **CLAIM**

The ornamental design for a pipe support, as shown and described.

DESCRIPTION

FIG. 1 is a front perspective view of a pipe support.

FIG. 2 is a front elevation view of the pipe support the rear view being a mirror image thereof.

FIG. 3 is a right side elevation view of the pipe support, the left side elevation view being a mirror image thereof.

FIG. 4 is a top plan view of the pipe support; and,

FIG. 5 is a bottom plan view of the pipe support.

The broken lines represent portions of the structure that forms no part of the claim.

1 Claim, 5 Drawing Sheets
